UNITED STATES PATENT OFFICE.

GEORGE ESLER KNOWLES, OF BROOKLYN, NEW YORK.

DESIGN FOR A PICTURE-DISPLAY CABINET.

No. 37,879.

Specification for Design.

Patented March 6, 1906.

Application filed January 23, 1906. Serial No. 297,522. Term of patent 7 years.

To all whom it may concern:

Be it known that I, GEORGE ESLER KNOWLES, a citizen of the United States, residing at Brooklyn, in the county of Kings and State of New York, have invented a new, original, and ornamental Design for Picture-Display Cabinets, of which the following is a specification, reference being had to the accompanying drawing, forming a part hereof.

The figure is a perspective view in eleva-

tion of a picture-display cabinet, showing my new design.

I claim—

The ornamental design for a picture-display cabinet, as shown.

GEORGE ESLER KNOWLES.
